UNITED STATES PATENT OFFICE.

LADISLAV GRUNTMAN, OF CHICAGO, ILLINOIS.

DESIGN FOR A GRATER-CASING.

52,475.

Specification for Design. Patented Sept. 24, 1918.

Application filed September 14, 1917. Serial No. 191,505. Term of patent 3½ years.

To all whom it may concern:

Be it known that I, LADISLAV GRUNTMAN, a citizen of the United States, residing in Chicago, in the county of Cook and State of Illinois, have invented a new, original, and ornamental Design for a Grater-Casing, of which the following is a specification, reference being had to the accompanying drawing, forming part thereof.

Fig. 2 illustrates a side elevation of same; Fig. 3 is a plan view.

I claim:

The ornamental design for a grater casing as shown.

In witness whereof, I have hereunto subscribed my name this 12th day of September 1917.

LADISLAV GRUNTMAN.
